ADJUSTING MEANS FOR TEXTILE DRAWING MECHANISMS

Erwin Dausch, Esslingen, Germany, assignor to S. K. F. Kugellagerfabriken, G. m. b. H., Schweinfurt, Germany

Application November 16, 1954, Serial No. 469,223

Claims priority, application Germany April 7, 1954

14 Claims. (Cl. 19—135)

The present invention relates to textile drawing mechanisms.

With conventional textile drawing mechanisms there are usually top rolls carrying arms each of which is provided with a plurality of individual top roll carriers shiftable along the arm so as to adjust the position of the top rolls. Each of these top roll carriers are fixed in their adjusted position independently. Thus, with the conventional arrangement it is necessary for the operator to release each of the shiftable carriers and to then fix each of these carriers in its adjusted position, and these operations are extremely inconvenient and require a considerable amount of time.

One of the objects of the present invention is to overcome the above drawbacks by providing a means which enables all of the shiftable carriers to be fixed releasably in their adjusted position with one single operation so that the release of all of the shiftable carriers and the fixing thereof in an adjusted position requires a very short time and may be carried out in an extremely simple way.

Another object of the present invention is to provide a means of the above type which is of an exceedingly simple construction.

A further object of the present invention is to provide a means of the above type which requires no special tools for releasing the carriers and for fixing the same in their adjusted position.

An additional object of the present invention is to provide a top rolls carrying arm with an extremely simple means for mounting and guiding the carriers for shifting movement along the arm.

Also, it is an object of the present invention to provide each top roll carriers with a means which automatically limits the movement of the top roll away from the carrier when the arm supporting the carrier is turned upwardly away from the drawing plane to an inoperative position.

With the above objects in view the present invention mainly consists of a drawing mechanism which includes a support means and a top rolls carrying arm carried by the support means for movement to and from an operating position where the arm extends over the drawing plane. A plurality of top roll carriers are distributed along the arm, these carriers respectively having top walls which overlie each other in all positions of the carriers on the arm. A mounting and guiding means is rigid with the arm and engages the carriers for guiding the same for shifting movement along the arm. Finally, a means is carried by the top rolls carrying arm and engages at least one of the carrier top walls for releasably preventing relative movement between these top walls so as to fix the position of the carriers on the arm after adjustment of the carriers along the arm.

The novel features which are considered as characteristic for the invention are set forth in particular in the appended claims. The invention itself, however, both as to its construction and its method of operation, together with additional objects and advantages thereof, will

be, best understood from the following description of specific embodiments when read in connection with the accompanying drawings, in which:

Fig. 1 is a partly diagrammatic and partly sectional, fragmentary side elevational view of a drawing mechanism, constructed in accordance with the present invention;

Fig. 2 is a sectional view taken along the line 2—2 of Fig. 1 in the direction of the arrows;

Fig. 3 is a sectional, fragmentary view taken along the line 3—3 of Fig. 1 in the direction of the arrows;

Fig. 4 is a fragmentary, partly sectional, side elevational view of a different embodiment of a structure constructed in accordance with the present invention;

Fig. 5 is a fragmentary, partly sectional, side elevational view of a third embodiment of a structure constructed in accordance with the present invention; and

Fig. 6 is a fragmentary, partly sectional, side elevational view of still another embodiment of a structure constructed in accordance with the present invention.

Referring now to Figs. 1—3 which illustrate one embodiment of the invention, a supporting frame 10 carries blocks 70, 71, and 72 which are shiftable along the frame 10 in any known way so that the positions of these blocks along the drawing plane may be adjusted, and any known means is provided to fix the blocks in their adjusted position. The blocks 70—72 respectively support the bottom rolls 11—13 for turning movement, as is evident from Fig. 1. A rod 14 is rigid with the frame 10 and carries a support 15 which has downwardly directed free end portions surrounding the rod 14 and releasably drawn toward each other by a screw means 16 for fixing the support 15 on the rod 14. Adjacent its top end the

support 15 carries a pivot pin 18 and extends between the side walls of a top roll carrying arm 17, the pivot pin 18 extending through suitable openings in these side walls so that the arm 17 is turnably carried on a support 15 by the pivot pin 18. In order to fix arm 17 in the operating position shown in Fig. 1, this arm 17 carries a lock member 19 which extends about the arm 17 and which has a top wall provided at its underside with a cylindrical surface portion engaging a cylindrical surface portion of the top wall of arm 17, as shown in Fig. 1, so that the lock member 19 is in this way supported for turning movement with respect to the arm 17. Lock 19 is provided with an extension 192 passing freely through an opening in the top wall of arm 17, and this extension 192 is itself formed with an opening through

which a wavy leaf spring 73 extends, as shown in Fig. 1, this spring 73 engaging the extension 192 and the bottom face of the top wall of the arm 17 so that the spring 73 urges the lock 19 to its locking position shown in Fig. 1. At its bottom end the lock 19 is provided with a cross member 191 which engages a forward extension 151 of the support 15 to maintain the arm 17 in the operating position shown in Fig. 1, and in order to release the arm 17 it is only necessary to turn lock 19 in a clockwise direction, as viewed in Fig. 1, so as to move cross member 191 out of engagement with extension 151.

The top rolls carrying arm is made out of sheet metal and has a substantially U-shaped cross section, the bottom of the arm 17 being opened and the channel shape of the arm providing the latter with a top wall and a pair of side walls. As was mentioned above these side walls at the rear end portion of arm 17 extend about the top end portion of the support 15. The front end of the arm 17 is closed by a wall 143.

As is particularly apparent from Fig. 2, the arm 17 is pressed inwardly along its opposite side edges to provide the arm 17 with inwardly extending projections 171 ex-

tending along the length of arm 17, and furthermore, between its top and bottom edges each of the side walls of the arm 17 is provided with an elongated inwardly struck portion 172 having an upwardly directed free edge, as shown in Fig. 2. The portions 171 and 172 extend along almost the entire length of the arm 17, as is apparent from Fig. 1. In the interior of the arm 17, the top free edges of the inwardly struck portions 172 and the bottom surfaces of the inwardly pressed projections 171 provide a mounting and guiding means for mounting and guiding individual top roll carriers, and as is apparent from Figs. 1 and 2 the intermediate carrier 27 of the three top roll carriers shown in Fig. 1 is itself of a substantially U-shaped cross section. As is apparent from Fig. 2 the carrier 27 is opened at its bottom and has its side walls engaging the inner surfaces of the side walls of the arm 17. The top surface of the carrier 27 is in slidable engagement with the bottom inner surface of the inwardly pressed portions 171, and the bottom free edges 272 of the carrier 27 are in slidable engagement with the top free edges of the inwardly struck portions 172. In this way, the carrier 27 is mounted within the arm 17 and the carrier 27 is shiftable along portions 171 and 172 of arm 17 so that these portions guide the carrier 27 for movement to a desired position along the arm 17.

A pair of rigid strips 75 are fixed respectively to the inner faces of the side walls of carrier 27 adjacent the rear end portion thereof, and these strips 75 extend freely about the inwardly struck portions 172, as is apparent from Fig. 2. A pin 29 extends between and is fixed to the strips 75, and a pressure arm 30 is pivotally carried by the pin 29. A coil spring 24 engages the top surface of arm 30 and the bottom surface of the top wall of carrier 27 so that this coil spring 24 tends to turn the arm 30 in a counterclockwise direction, as viewed in Fig. 1. At its free end portion the arm 30 is fixed to and carries a saddle 76 which engages the shaft 78 of top roll 21, and a leaf spring 77 is fixed to saddle 76 and engages shaft 78 to turnably connect the top roll 21 to the saddle. A substantially L-shaped stop member 273 is fixed to and extends downwardly from the top wall 271 of carrier 27, and a second L-shaped stop member 301 is fixed to and extends upwardly from the arm 30, these stop members being inverted with respect to each other so that the stop member 273 is located in the path of movement of stop member 301 when the arm 30 turns about pin 29 upon raising of the arm 17, as is apparent from Fig. 1. Thus, the stop member 301 will move into engagement with the stop member 273 to limit the turning of the arm 30 and top roll 21 away from carrier 27 during movement of the arm 17 to its inoperative position.

A forward carrier 26 is located ahead of carrier 27 and a rear carrier 28 is located behind the carrier 27, and these carriers 26 and 28 have the same cross section as the carrier 27. The carrier 26 has its bottom free edges in engagement with the top free edges of inwardly struck portions 172, and the carrier 28 has its bottom free edges 282 in slidable engagement with the top free edges of inwardly struck portions 172, and both of these carriers are in slidable engagement with the inwardly pressed portions 171, so that in this way the carriers 26 and 28 are also shiftable along the arm 17. Fig. 3 clearly illustrates how the carrier 26 is mounted and guided in this manner, and the carrier 28 is mounted and guided in a similar way. The stop members 263 and 283 of the carriers 26 and 28, respectively, are identical with stop member 273, and the remainder of the structure for interconnecting the top rolls 20 and 22 with the carriers 26 and 28, respectively, is identical with the above described structure of carrier 27, and the elements of these structures are provided with the same members. The carriers 26 and 28 are, however, different from carrier 27 in that the top walls of carriers 26 and 28 are considerably longer than the top wall of the carrier 27. Thus, the top wall of carrier 26 includes an extension 264 which extends over

the carrier 27, and the top wall of the carrier 28 includes an extension 284 which also extends over the carrier 27, so that the top walls of the three carriers are in overlying engagement with each other. The length of the extensions 264 and 284 is such that they remain in overlying engagement with each other and with the carrier 27 beneath the screw 32 of Fig. 1 in all positions of the top rolls. Thus, when the top rolls are shifted the carriers 26 and 28 will move and will cause the extensions 264 and 284 to shift with respect to each other as well as with respect to the carrier 27 which may also be shifted. This screw 32 extends threaded through a threaded opening in the top wall of the arm 17, and the screw 32 is provided with a bottom enlarged end which engages the uppermost of the overlying top walls of the several carriers, the extension 264 in the example shown in Fig. 1. The screw member 32 is provided in its top face with a suitable slot to receive a screw driver, for example, and it is evident that by turning the screw 32 downwardly against the top walls the latter are pressed tightly together so as to prevent shifting of the carriers, while at the same time the screw 32 may be loosened to release the carriers for shifting movement. In this way but a single quick operation is required to release the carriers and to fix the same.

Fig. 4 illustrates a second embodiment of the invention, and all of the parts shown in Fig. 4 which are identical with the corresponding parts of Figs. 1-3 are indicated with the same reference characters. The top rolls carrying arm 42 of Fig. 4 differs from arm 17 only in that the top wall of arm 42 is provided with a pair of upwardly extending portions carrying a pivot pin 41 which is fixed to these upwardly extending portions, and the arm 42 is provided in its top wall with a cutout through which a handle 43 freely extends, as shown in Fig. 4, this handle 43 being rigidly fixed to a cam 40 which is eccentrically carried by the pin 41 for turning movement to and from the position shown in Fig. 4. In the position of the parts illustrated in Fig. 4, the cam 40 presses the top wall 271 of carrier 27 and the extensions 264 and 284 of carriers 26 and 28, respectively, together so as to releasably fix the carriers in an adjusted position along the arm 42. In order to release the carriers for shifting movement along the arm 42, it is only necessary to turn the handle 43 upwardly so as to turn the cam 40 in a counterclockwise direction about the pin 41, and as is evident from Fig. 4 this operation will release the carriers.

A third embodiment of the invention is illustrated in Fig. 5 which again indicates those parts identical with corresponding parts of the above described embodiments with the same reference characters. The top rolls carrying arm 50 of Fig. 5 is identical with the top rolls carrying arm 17 except that the arm 50 is formed in its top wall with an opening and is provided with a tubular member 503 fixed to the top wall of arm 50 and forming a downwardly extending extension of the opening in the top wall of the arm 50. A pin 51 is slideable in the tubular member 503 and extends upwardly beyond the arm 50, as is evident from Fig. 5. At its bottom end the pin 51 is provided with an enlarged portion 511 engaged by the bottom end of a coil spring 52 which extends about the tubular member 503 and engages the bottom surface of the top wall of the arm 50. Thus, the spring 52 urges the pin 51 downwardly so that the pin 51 presses the top wall 271 of carrier 27 and the extensions 264 and 284 together to maintain the three carriers in an adjusted position.

At its top free end portion above the arm 50 the pin 51 is provided with an annular groove 512 into which the tines 541 of the forked end of a lever 54 extend. This lever 54 is bent, as shown in Fig. 5, so that when the right free end of lever 54, as viewed in Fig. 5, is pressed downwardly the tines 541 will raise the pin 51 against the influence of the spring 52 to release the carriers for shifting movement along the arm 50. The

pin 51 may be raised until the enlargement 511 thereof engages the bottom end 502 of the tubular member 503.

Fig. 6 illustrates a fourth embodiment of the invention wherein elements identical with those of the above-described embodiment are indicated with the same reference characters. The top rolls carrying arm 60 of Fig. 6 is provided along its opposite upper side edges with inwardly pressed portions 601 corresponding to the inwardly pressed portions 171, and furthermore, the side walls of the arm 60 are formed with inwardly struck portions 602 providing top free guiding edges in the same way as the inwardly struck portions 172 described above. Between the guides 601 and 602 an intermediate carrier 62 is shiftably arranged in the same way as the carrier 27, and in a similar way this carrier 62 is provided with a stop member 623 corresponding in all respects to the stop member 273. A rear carrier 63 is provided with a top wall which includes an extension 634 extending over the top wall 621 of the carrier 62, and Fig. 6 shows only the extension 614 of the top wall of a front carrier which is not shown in Fig. 6 and which corresponds in all respects to the carrier 26 of Fig. 1. The extension 614 is provided with a plurality of openings distributed along the length thereof, the extension 634 is similarly provided with a plurality of openings 68, and the top wall 621 of carrier 62 also is provided with a plurality of openings 68. The openings 68 of the several top walls are spaced equally from each other so that the three carriers may be shifted to several positions where at least one of the openings of one of the top walls is in alignment with at least one of the openings of the other top walls. A pin 641 in the form of a free end portion of a lever 64 extends through one of the groups of aligned openings 68 in the manner shown in Fig. 6, all of the openings 68 being of the same diameter. The lever 64 is pivotally carried by a pin 65 extending through an opening of lever 64 and extending between and fixed to the side walls of the arm 60. A spring 66 engages the lever 64 and the top wall of arm 60 to urge the lever 64 in a counter-clockwise direction, as viewed in Fig. 6, to the position shown in Fig. 6, where the pin 641 extends through a group of aligned openings 68 and prevents shifting movement of the carriers. A pin 67 is slideable through an opening in the top wall of arm 60, and the bottom end portion 671 of the pin 67 engages the lever 64 in the manner shown in Fig. 6. Thus, in order to release the carriers of Fig. 6 for shifting movement along the arm 60 it is only necessary for the operator to depress pin 67 so as to turn the lever 64 in a clockwise direction, as viewed in Fig. 6, about pin 65 and against the influence of the spring 66, so as to raise the free end portion 641 of lever 64 out of the opening 68 to release the carriers for shifting movement to a position where a different group of openings 68 are aligned beneath the free end portion 641 so that when the pin 67 is released the spring 66 may move the pin-shaped portion 641 of lever 64 through this group of aligned openings 68 to again lock the carriers in their adjusted position.

The top right end portion of Fig. 1 shows a leaf spring fixed to the underside of the top wall of arm 17 and having a curved right free end portion, as viewed in Fig. 1, which is adapted to enter a recess in support 15 shown adjacent the upper right portion of support 15 so as to releasably maintain the arm 17 in its inoperative position away from the drawing plane.

It will be understood that each of the elements described above, or two or more together, may also find a useful application in other types of drawing mechanisms differing from the types described above.

While the invention has been illustrated and described as embodied in adjustable drawing mechanisms, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a drawing mechanism, in combination, support means; a top rolls carrying arm carried by said support means for movement to and from an operating position where said arm extends over the drawing plane; a pair of top roll carriers spaced along said arm, one of said carriers having an extension extending over and engaging the other of said carriers; mounting and guiding means rigid with said arm and engaging said carriers for guiding the same for shifting movement along said arm; and means carried by said arm and engaging said extension for releasably preventing relative movement between said extension and said other carrier whereby after the position of said carriers along said arm is adjusted said last-mentioned means releasably fixes said carriers in their adjusted position.
2. In a drawing mechanism, in combination, support means; a top rolls carrying arm carried by said support means for movement to and from an operating position where said arm extends over the drawing plane; a plurality of roll carriers distributed along said arm, all except one of said carriers having extensions engaging each other and extending over said one carrier; mounting and guiding means rigid with said arm and engaging said carriers for guiding the same for shifting movement along said arm; and means carried by said arm engaging one of said extensions for releasably preventing relative movement between said extensions and said one carrier whereby after the position of said carriers along said arm is adjusted said last-mentioned means releasably fixes said carriers in their adjusted position.
3. In a drawing mechanism, in combination, support means; a top rolls carrying arm carried by said support means for movement to and from an operating position where said arm extends over the drawing plane; a plurality of top roll carriers distributed along said arm, said carriers respectively having top walls which overlie each other in all positions of said carriers on said arm; mounting and guiding means rigid with said arm and engaging said carriers for guiding the same for shifting movement along said arm; and means carried by said arm and engaging at least one of said top walls for releasably preventing relative movement between said top walls so as to fix the position of said carriers on said arm after adjustment of said carriers along said arm.
4. In a drawing mechanism, in combination, support means; a top rolls carrying arm carried by said support means for movement to and from an operating position where said arm extends over the drawing plane; a plurality of top roll carriers distributed along said arm, said carriers respectively having top walls which overlie each other in all positions of said carriers on said arm; mounting and guiding means rigid with said arm and engaging said carriers for guiding the same for shifting movement along said arm; and means carried by said arm for releasably pressing said top walls into engagement with each other for releasably preventing shifting of said carriers along said arm.
5. In a drawing mechanism, in combination, support means; a top rolls carrying arm carried by said support means for movement to and from an operating position where said arm extends over the drawing plane; a plurality of top roll carriers distributed along said arm, said carriers respectively having top walls which overlie each

other in all positions of said carriers on said arm, said top walls each being formed in its overlying portion with a plurality of openings distributed along said top wall and said openings being aligned; mounting and guiding means rigid with said arm and engaging said carriers for guiding the same for shifting movement along said arm; a pin extending through a group of aligned openings of said top walls, respectively, to prevent shifting of said top walls with respect to each other; and manually operable means engaging said pin for moving the same out of said openings to release said carriers for shifting movement to another adjusted position where another group of openings of said top walls are in alignment to receive said pin and thus maintain the carriers in their adjusted position.

6. In a drawing mechanism, in combination, support means; a top rolls carrying arm carried by said support means for movement to and from an operating position where said arm extends over the drawing plane; a plurality of top roll carriers distributed along said arm, said carriers respectively having top walls which overlie each other in all positions of said carriers on said arm; mounting and guiding means rigid with said arm and engaging said carriers for guiding the same for shifting movement along said arm; and screw means threadedly carried by said arm and engaging the uppermost of said top walls, whereby said screw means may be turned to press said top walls together so as to prevent shifting of said carriers and to release said top walls to free said carriers for shifting movement.

7. In a drawing mechanism, in combination, support means; a top rolls carrying arm carried by said support means for movement to and from an operating position where said arm extends over the drawing plane; a plurality of top roll carriers distributed along said arm, said carriers respectively having top walls which overlie each other in all positions of said carriers on said arm; mounting and guiding means rigid with said arm and engaging said carriers for guiding the same for shifting movement along said arm; and cam means turnably carried by said arm, engaging the uppermost of said top walls, and being turnable between a locking position where said cam means presses said top walls together to prevent shifting of said carriers and a release position freeing said carriers for movement with respect to each other along said arm.

8. In a drawing mechanism, in combination, support means; a top rolls carrying arm carried by said support means for movement to and from an operating position where said arm extends over the drawing plane; a plurality of top roll carriers distributed along said arm, said carriers respectively having top walls which overlie each other in all positions of said carriers on said arm; mounting and guiding means rigid with said arm and engaging said carriers for guiding the same for shifting movement along said arm; a pin carried by said arm for movement into and out of engagement with one of said top walls; spring means engaging said pin and urging the same into engagement with said one top wall for pressing said top walls together so as to prevent shifting movement of said carriers with respect to each other; and manually operable means engaging said pin for moving the same against the influence of said spring means away from said one top wall to release said carriers for shifting movement with respect to each other along said arm.

9. In a drawing mechanism, in combination, an elongated top rolls carrying arm; support means supporting said arm for movement to and from an operating position where said arm extends over the drawing plane; three top roll carriers distributed along said arm with one of said carriers located between the other two, the latter two carriers having top walls extending over and along said one carrier and overlying each other and said one carrier; mounting and guiding means rigid with said arm for

mounting said carriers thereon and for guiding said carriers for shifting movement along said arm; and means carried by said arm over said one carrier and engaging at least the uppermost of said top walls for releasably preventing movement of said top walls with respect to each other.

10. In a drawing mechanism, in combination, an elongated top rolls carrying arm; support means supporting said arm for movement to and from an operating position where said arm extends over the drawing plane; three top roll carriers distributed along said arm with one of said carriers located between the other two, the latter two carriers having top walls extending over and along said one carrier and overlying each other and said one carrier; mounting and guiding means rigid with said arm for mounting said carriers thereon and for guiding said carriers for shifting movement along said arm; and a screw member threadedly carried by said arm over said one carrier and engaging the uppermost of said top walls for releasably pressing said top walls against each other to prevent movement of said top walls with respect to each other.

11. In a drawing mechanism, in combination, an elongated top rolls carrying arm; support means supporting said arm for movement to and from an operating position where said arm extends over the drawing plane; three top roll carriers distributed along said arm with one of said carriers located between the other two, the latter two carriers having top walls extending over and along said one carrier and overlying each other and said one carrier; mounting and guiding means rigid with said arm for mounting said carriers thereon and for guiding said carriers for shifting movement along said arm; a cam turnably carried by said arm over said one carrier and engaging the uppermost of said top walls for releasably pressing said top walls against each other to prevent movement of said top walls with respect to each other; and a handle fixed to said cam for manually turning the same.

12. In a drawing mechanism, in combination, an elongated top rolls carrying arm; support means supporting said arm for movement to and from an operating position where said arm extends over the drawing plane; three top roll carriers distributed along said arm with one of said carriers located between the other two, the latter two carriers having top walls extending over and along said one carrier and overlying each other and said one carrier; mounting and guiding means rigid with said arm for mounting said carriers thereon and for guiding said carriers for shifting movement along said arm; a pin over said one carrier extending slidably through said arm, engaging the uppermost of said top walls, and having a free end portion extending outwardly beyond said arm; spring means engaging said pin for urging the latter into engagement with said uppermost top wall so as to releasably prevent shifting of said carriers with respect to each other; and a handle engaging said free end portion of said pin for enabling the operator to move said pin against the influence of said spring away from said uppermost top wall to release said carriers for independent shifting movement along said arm.

13. In a drawing mechanism, in combination, an elongated top rolls carrying arm; support means supporting said arm for movement to and from an operating position where said arm extends over the drawing plane; three top roll carriers distributed along said arm with one of said carriers located between the other two, the latter two carriers having top walls extending over and along said one carrier and overlying each other and said one carrier, each of said top walls being formed with a plurality of openings distributed along said arm, and the openings of said top walls being in alignment with each other; mounting and guiding means rigid with said arm for mounting said carriers thereon and for guiding said carriers for shifting movement along said arm; a lever turnably carried by said arm and having a free end portion

extending through one group of aligned openings to prevent shifting movement of said carriers along said arm; spring means urging said lever to a position where said free end portion thereof extends through said aligned openings; and manually operable means carried by said arm and engaging said lever for turning the latter against the influence of said spring means to a position where said free end portion is out of said openings and said carriers are thus released for shifting movement along said arm.

14. In a drawing mechanism, in combination, an elongated top rolls carrying arm; support means supporting said arm for movement to and from an operating position where said arm extends over the drawing plane; three top roll carriers distributed along said arm with one of said carriers located between the other two, the latter two carriers having extensions, respectively, extending over and along said one carrier and overlying each other and said one carrier; mounting and guiding means rigid with said arm for mounting said carriers thereon and for guiding said carriers for shifting movement along said arm; and a single releasable fixing means carried by said

5 arm over said one carrier and engaging at least the uppermost of said extensions for releasably preventing movement of said carriers with respect to each other, said fixing means extending through said arm to the exterior thereof so as to be accessible to the operator.
